UNITED STATES PATENT OFFICE.

EDWARD CAIRNS, OF MONTCLAIR, NEW JERSEY, ASSIGNOR TO CONSOLIDATED SAFETY PIN COMPANY, OF BLOOMFIELD, NEW JERSEY, A CORPORATION OF NEW JERSEY.

MACHINE FOR PUTTING COIL-GUARDS ON SAFETY-PINS.

1,177,926.

Specification of Letters Patent. Patented Apr. 4, 1916.

Application filed May 14, 1915. Serial No. 27,983.

To all whom it may concern:

Be it known that I, EDWARD CAIRNS, a citizen of the United States, residing in Montclair, Essex county, State of New Jersey, have invented certain new and useful Improvements in Machines for Putting Coil-Guards on Safety-Pins, of which the following is a specification, reference being had to the accompanying drawings, forming a part hereof.

Safety pins which have the body wire coiled between the back and the point member are commonly provided each with a guard for the coil to prevent the fabric which is entered by the point member from becoming entangled in the coil. A highly efficient form of such guard consists of a small piece of thin sheet metal which is perforated to receive the point member and is crimped on the coil.

The object of this invention is to produce a machine by which guards of the general character of those referred to, whether of the same form or not, may be applied automatically and rapidly to the pins, the guards being preferably formed in the same machine.

The invention will be more fully explained hereinafter with reference to the accompanying drawings in which it is illustrated as embodied in a practical and efficient form of mechanism.

In the drawings—Figure 1 is a view of the machine in perspective, actuating mechanism which is not necessary to an understanding of the invention being omitted and some parts being broken away. Fig. 2 is a detail top view showing the traveling die-plate with some of the parts associated therewith. Fig. 3 is a view of the machine in elevation as seen from a point of view nearly opposite that of Fig. 1, on a slightly larger scale than that of Fig. 1 and with some parts broken away. Fig. 4 is a view of the strip of sheet metal from which the guards are formed, a portion of the strip being shown in blank, another portion with the holes for the pin points punched therein, and another portion with the guard blanks punched out. Figs. 5 and 6 are detail views of a guard in successive stages of formation. Fig. 7 is a detail view, partly in section, and on a considerably larger scale than that of Fig. 3, showing the strip from which the guards are formed, with the devices for first punching the strip and then

blanking and drawing the guard with the means for supporting the strip during these operations and the traveling die-plate which cooperates with the blank and drawing device. Fig. 8 is a perspective view of the devices which are directly concerned with the feeding and bodily movement of the safety pins upon which the guards are to be placed, as seen generally from the point of view of Fig. 1, but on a larger scale and with the holding plate in section and some parts broken away. Figs. 9 and 10 are detail views of the same mechanism in elevation and in vertical section on different planes. Fig. 10^a is a detail perspective view of a portion of the devices shown in Figs. 9 and 10. Figs. 11 and 12 are detail views of a portion of the pin feeding devices. Fig. 13 is a detail view in section illustrating particularly the devices for closing the pin. Fig. 14 is a detail view in section illustrating particularly the devices discharging the completed and closed pin from the machine. Fig. 15 is a perspective view, on an enlarged scale, of the pin with the guard in place but before it is crimped in. Fig. 16 is a detail view in section on the plane indicated by the line 16—16 of Fig. 15. Fig. 17 is a view in perspective, on an enlarged scale, of the pin closed and with the guard crimped in place. Fig. 18 is a view in section on the plane indicated by the line 18—18 of Fig. 17.

The machine illustrated herein as an embodiment of the invention comprises a bed-plate *a* upon which are supported certain parts of the mechanism hereinafter referred to, the bed-plate being provided also with a standard *a'* which supports certain other parts of the mechanism hereinafter referred to, and also supports at its upper end the main actuating shaft of the machine, with its appurtenances, which shaft and appurtenances, being substantially such as are found in any ordinary punch press, are not necessary to be shown herein. The bed-plate *a* is also provided with a circular boss *a*².

The annular, traveling die-and-guard carrier *b* is supported on the bed-plate *a* and is guided by the boss *a*². It is provided at equally spaced intervals with dies *b'* each formed at the top with a recess *b*², suitably shaped for the formation of the guard in conjunction with the blanking and drawing plunger hereinafter referred to, having a

trefoil outline at the top, and entered, to the center, by a radial slot b^8 from the edge of the carrier b . Secured to the carrier b is a ratchet ring b^4 which, in order that the carrier may be advanced with a step by step movement, is engaged by a driving pawl c and by a holding pawl c' . The driving pawl c may be actuated by any suitable means. As shown in Figs. 1 and 2 of the drawings, it is pressed by a spring c^2 toward the ratchet ring, is pivoted at c^3 upon a slide c^4 and is provided with a handle c^5 by which it may be disengaged from the ratchet ring. The slide c^4 is actuated from 15 the actuating shaft of the machine, in synchronism with other mechanism, through a link c^6 , a bell crank c^7 and a rod c^8 .

Means are also provided for insuring the accurate positioning of the carrier before 20 the several operations, which must be performed while the carrier is at rest, are initiated. For this purpose the carrier is provided with holes b^5 to be engaged in succession, after each forward movement of 25 the carrier, by a clutch-controlling pin d guided for vertical movement in a fixed guide d' and carried by an arm d^2 from a vertical rod d^3 , which is actuated at the proper time from the main actuating shaft 30 and is connected, in any suitable manner, with the clutch through which the main actuating shaft is driven.

The guards which are to be applied to the pins are preferably formed in the machine 35 itself, being placed in the dies b' , and are then transported in the carrier, from the point at which they are formed, in succession, to the point at which they are engaged in succession by the pins to which they are 40 applied. They are formed from a strip or ribbon e of sheet metal which is fed into the machine, with a step-by-step movement, by any suitable strip feeding device. As shown such device may consist of a pair of rollers 45 e' , one of which is actuated, with a step-by-step movement, by a pawl arm e^2 which is struck and moved in one direction by a pin e^3 , carried by the reciprocating head f hereinafter referred to, and is returned by a 50 spring, as usual in devices of this character, the details of which are well known and need not be illustrated or described herein. The strip is fed across the carrier b through a strip guide e^8 which is provided with a 55 punch-hole e^4 and with a plunger opening e^5 . On the under side of the reciprocating head f are mounted a punch e^6 in line with the hole e^4 , and blanking and drawing plungers e^7 and e^{17} , the former cutting the blank 60 from the strip in conjunction with the opening e^5 in the guide e^8 and the latter, which is central with respect to the former and also has a delayed movement with respect thereto carrying the blank, when it has been 65 cut, down into the die and giving it the form

shown in Fig. 5. The reciprocating head f receives its downward movement from the actuating shaft at a time when the strip e is stationary, the punch e^6 making, in the proper position in the strip e , a hole e^8 , 70 which is subsequently entered by the point member of the pin, and the plungers e^7 and e^{17} cutting from the strip the blank which subsequently forms the guard, and forming it as described, each blank including the hole e^8 previously formed. The shape of the blank is indicated by the holes e^9 , shown in Fig. 4, left in the strip by the cutting out of the blanks. As each blank is cut out by the plunger e^7 it is drawn into shape, as shown at g in Fig. 5, by the plunger e^{17} which forces it into the cavity of the die b' . At the next forward movement of the carrier b the die b' which has just received the guard, is carried forward into line with another plunger e^{10} , also carried by the reciprocating head f , and the ears g' , which at the first operation were left standing upright, as shown in Fig. 5, are turned outwardly, as shown in Fig. 6.

When the guard has thus been formed, with the hole e^8 therein, it is transported by the carrier b to the position where the point member of the pin is made to pass through the hole e^8 in the guard and its coil is 90 brought into juxtaposition to the guard. Before the devices for moving the pin bodily into engagement with the guard are described, it will be necessary to describe such means as are shown for feeding the pins, 100 one at a time, into position to be engaged by such devices. The pins might be delivered to the feeding devices directly from the pin forming machine, without the intervention of the hand, but they may be placed by hand in or on the feeding means. As shown in the drawings, the open pins are 105 supposed to be placed by hand on an inclined rail h , with the point members all at one side and the backs at the other side and resting at the coil end on the upper edge of the rail h , the inclination of which is sufficient to cause the pins to slide toward the lower end. Guard rails h' , spaced 110 slightly from the feed rail h , may be provided to prevent the pins from jumping one upon another as they are placed on the rail h and slide downwardly thereon. At the lower end of the rail h is a pin releasing device, shown particularly in Figs. 9, 11 and 12, adapted to release one pin at a time and permit it to pass into position to be engaged by the devices which move it onward. This pin releasing device comprises a flat spring h^2 secured over a recess h^3 in the rail h , 115 flush with the surface, and provided at its lower end with one or two projecting stops h^4 . Arranged to coöperate with the spring h^2 , so as to depress the same and permit the lowermost pin to escape over the stops h^4 , 120 125 130

but preventing the escape of the other pins on the rail h is a spring depressor h^5 which has a narrow tooth h^6 adapted to make contact with the spring between the lowermost 5 pin, which rests against the stops h^4 , and the next pin, as shown clearly in Fig. 11. This depressor h^5 is operated at the proper time from the main actuating shaft of the machine through the reciprocating head f , the depressor h^5 being carried by a lever h^7 which is moved in one direction by a spring h^8 to withdraw the depressor and is moved in the other direction, to depress the spring h^2 by a finger h^9 carried by the reciprocating 10 head f . Each pin leaves the rail h with the point member substantially vertical and directed downward and in this position the pin is pushed down to cause the point member to enter the hole e^8 in the guard g which 15 is then in line with the point member of the pin, the downward movement of the pin being continued until the coil of the pin enters the cup-shaped guard. It is necessary, however, that the pin be held, as it leaves the 20 rail h , with the point member vertical, but in such manner that the pin can be pushed down, and that means be provided for truing or correcting the position of the pin, in case it should not be placed accurately, and 25 for guiding it in its downward movement until such movement is completed. Such devices will now be described.

As shown particularly in Figs. 3, 8 and 10, there is placed opposite the discharge end 30 of the pin feeding devices a guide plate i , which is grooved vertically as at i' and i^2 but otherwise opposes to the pin feeding devices a smooth face. Coöperating with this plate i is a presser arm i^3 which is pivoted at 35 i^4 on a fixed standard, has a straight lower arm i^5 , has connected thereto at the other side of the pivot a rod i^6 under spring tension, which tends to hold the straight arm i^5 normally toward the plate i , and an arm 40 i^7 with a toe i^8 , which is adapted to be struck, in the downward movement of the reciprocating head f , by a finger i^9 carried by the head, so as to move the straight part i^5 of 45 the presser away from the plate sufficiently 50 to release the pin which has theretofore been held by its pressure against the plate i and to permit the next pin from the feeding devices to enter between the straight part i^5 and the plate i so as to be grasped and held 55 thereby as soon as the upward movement of the head f permits the presser to be swung on its pivot by the spring rod i^6 . The presser i^5 is preferably arranged to bear against the shield of the pin and two horizontally movable, spring-pressed presser blocks i^{10} and i^{11} , having rounded ends, as shown clearly 60 in Fig. 8, bear against the coil of the spring as it is pushed down pressing it against the plate i . These two pressure devices, the 65 pivoted presser i^3 and the presser blocks

i^{10} and i^{11} , retain the pin with its point member vertical but permit it to be pushed down in this relative position.

Since the point member of the pin, as it leaves the feeding devices, may not stand in a truly vertical position, it is necessary to provide truing devices which shall insure the truly vertical position of the point member and so hold it until the point enters the point guide hereinafter mentioned. Such truing devices comprise upper and lower guide plates k and k^1 , which are separated by a slot or space k^2 , as clearly shown in Figs. 9 and 10, these plates flaring outward slightly from the line of travel of the point member, and a truing plate k^3 which has in its forward edge a notch k^4 , and is adapted to enter the space or slot between the upper and lower fixed plates k and k^1 . The truing plate is secured to an arm k^5 which is pivoted on a standard k^6 and is acted upon by a spring k^7 so that the truing plate is held normally in the position shown by full lines in Figs. 9 and 10, with the notch k^4 forming a guide for the point member. The shoulder 85 of the arm k^5 , as shown in Fig. 9, stands in the path of a finger k^8 which is carried by the reciprocating head f , so that as the head approaches the limit of its downward stroke the finger k^8 strikes the shoulder of the arm 90 k^5 and swings the arm from the position shown by full lines in Figs. 9 and 10 to the position indicated by dotted lines in Fig. 9, whereby the truing plate k^3 is swung away 95 so as to permit the coil of the pin to pass it 100 in its continued downward movement, the truing plate being held in this position long enough to permit the point member of the next pin from the feeding devices to drop into position to be engaged by the truing plate when it is permitted to swing back into 105 normal position.

While the pin is thus held yieldingly and guided it is pushed downward by two fingers m and m' which are carried by the reciprocating head f and are guided in the grooves i' and i^2 of the plate i . The lower end of the finger m is suitably formed to engage the coil end of the pin while the lower end of the finger m' is suitably formed to 115 engage the back of the pin.

Since the point of the pin must enter the comparatively small hole e^8 in the guard, it is desirable to provide a guide for the point of the pin just above the carrier b , which 120 guide will yield to permit the full movement of the coil end of the pin. The point guide is therefore formed as a suitably shaped recess n , in one side of a block n' which is carried by an arm n^2 , as shown in Fig. 8. The arm n^2 is pivotally mounted on the portion a^2 of the bed-plate a and has connected thereto a spring n^3 by which it is held yieldingly in the position shown in Figs. 1 and 8, being capable of being moved 125 130

away from its normal position by the coil of the spring as it descends.

When the point member of the pin has been passed through the guard, as already described, the next step is to crimp the guard or to pinch in the ears g' of the guard so that the guard shall be retained in place on the coil. Accordingly the pin and the guard, with the point member of the pin resting against a cam rail o and with the guard still held in the die b' , are carried along from the pin inserting devices to a position for the operation of the crimping devices. The latter comprise two crimping jaws p pivoted in a support p' carried by the reciprocating head f , as shown in Figs. 1 and 3. The jaws are provided each with a pin p^2 , one of which is shown in Fig. 3, which project through the side of the support p' and are acted upon by a spring p^3 so that they are held normally apart. As the head f descends, the jaws, which are suitably curved on their lower ends, pass down outside of the ears g' and are then caused to move toward each other by the opposite inclined walls of the trefoil recess in the top of the die, thereby pinching in the ears g' so that they meet or nearly meet within the coil of the spring and thereby secure the guard in place.

The next operation, which may be simultaneous with the crimping of the guard, is the closing of the pin, that is, the engagement of the pin point with the shield. As the pin moves on with the carrier b , still being held with the guard in the die, the point member is supported by a cam rail o . While it is thus supported a finger r , see Figs. 3 and 13, carried by the support p' in the descending movement of the reciprocating head, being suitably forked at its lower end as shown plainly in Fig. 3, strikes the projecting back member of the pin and forces it down until its shield is engaged by the pin point.

In view of the possibility that in the operation of closing the pin the coil end might be lifted slightly out of place, so that it might not be properly engaged by the extracting devices hereinafter described, the coil end is settled into place, at the same time with the closing of the pin and with the crimping of the guard, by a finger r' which is also carried by the support p' , between the jaws p . A guard rail r^2 , as shown in Fig. 13, may be provided to prevent the pins from jumping up and for holding them down in proper position for the operation of the finger r . Finally the closed pin is extracted from the die, in which the guard plate, crimped upon the coil, is still held frictionally, and is ejected from the machine. The extraction of the pin from the carrier is accomplished by a gripping device s which is carried by a support s' on

the under side of the reciprocating head f . This gripper s consists of two members s^2 and s^3 , as shown clearly in Figs. 3 and 14, which are pivoted in the support s' and are provided each with two fingers s^4 and s^5 . The two fingers s^4 , being relatively short, are adapted to engage the coil of the pin, while the two fingers s^5 , being longer, are adapted to engage the pin near the shield end. The object in view in providing the two sets of fingers is to lift the pin with a parallel motion and without causing any turning of the coil end in the die, which might injure the guard. The gripper is caused to close upon the pin, as the reciprocating head completes its downward movement, through the coöperation of the curved fingers s^4 with the sides of the dished, trefoil recess in the top of the die. The two grippers are held frictionally but quite tightly in the support s' and therefore lift the pin from the carrier as the reciprocating head f ascends. As the reciprocating head approaches the limit of its upward movement it is necessary that the grippers be opened so as to release the pin. For this purpose there is pivoted in the support s' an opener s^6 which has at its inner end a nose s^7 adapted to enter between the grippers s^2 and s^3 to spread them apart at the proper time, and an arm s^8 which is engaged, at the proper time, by a stop s^9 . This stop s^9 is so supported from the bed-plate a or from the standard a' , as may be convenient, that it is engaged by the arm s^8 as the reciprocating head approaches the limit of its upward movement, so that the pin is released by the grippers at or near the highest position reached by it. As the pin falls from the grippers, it falls upon a plate t which is hinged, with a spring hinge t' , at the upper end of a standard t^2 , fixed on the boss a^2 of the bed-plate. As the reciprocating head f descends, the plate t is pushed back by the support s' , out of the way, but as the head ascends the plate t swings forward quickly, intercepting the falling pin and directing it away from the carrier into the discharge chute t^3 .

It will be understood that although the machine and its operations have been described with reference to the operations performed upon a single guard and a single pin, each die of the carrier b receives a guard and as each guard is brought in line with the pin feeding devices it receives a pin, the guard being then crimped and the pin closed, extracted and ejected.

It will also be understood that some of the operations herein described, such, for example, as the formation of the guard in the machine, and the closing of the pin, might be omitted without affecting the performance of the other operations.

It will also be obvious that various

changes in details of construction and arrangement within the scope of the claims may be made to adapt the machine for operation upon pins of different sizes and different styles.

5 I claim as my invention:—

1. A machine for assembling safety pins and coil guards therefor comprising a carrier for the guards, means for supporting a plurality of pins in readiness to move forward, means for releasing the pins one by one from the pin supporting means, and means of moving each pin as it is released into operative relation with its coil guard

15 as the latter is presented.

2. A machine for assembling safety pins and coil guards therefor comprising a carrier for the guards, an inclined rail upon which the pins are placed, means for releasing the pins one by one from the rail, and means for moving each pin in succession into operative relation with its coil guard as the latter is presented.

25 3. A machine for assembling safety pins and coil guards therefor comprising a carrier for the guards, an inclined rail upon which the pins are placed, a flat spring parallel with the rail and having a projection to engage the lowermost pin, and a reciprocating device having a point to enter between the lowermost pin and the next pin and to depress the spring so as to release the lowermost pin.

35 4. In a machine of the character described, the combination of pin feeding devices, a plate against which each pin is delivered from the feeding devices and in contact with which it slides, and a yielding, spring-presser adapted to hold each pin as it is delivered by the feeding devices frictionally against the plate.

40 5. In a machine of the character described, the combination of pin feeding devices, a plate against which each pin is delivered from the feeding devices and in contact with which it slides, a yielding, spring-presser adapted to hold each pin as it is delivered by the feeding devices frictionally against the plate, and means for advancing the pin while it is held frictionally by the presser.

45 6. In a machine of the character described, the combination of pin feeding devices, a plate against which each pin is delivered from the feeding devices and in contact with which it slides, a yielding, spring-presser adapted to hold each pin as it is delivered by the feeding devices frictionally against the plate, means for advancing the pin while it is held frictionally by the presser, and means for truing the position of the pin.

50 7. In a machine of the character described, the combination of pin feeding devices, a plate against which each pin is de-

livered from the feeding devices, a presser adapted to hold each pin as it is delivered by the feeding devices frictionally against the plate, means for advancing the pin while it is held frictionally by the presser, 70 means for truing the position of the pin, and a yielding point guide for the pin.

8. A machine for assembling safety pins and coil guards therefor comprising a carrier for the guards, means for advancing the carrier with a step-by-step motion, devices for supporting a plurality of pins and feeding them forward by gravity, means to release the pins one by one from the feeding devices, and means for moving each pin as it is released into operative relation with its coil guard as the latter is presented.

85 9. A machine for assembling safety pins and coil guards therefor comprising a carrier for the guards, means for advancing the carrier with a step-by-step motion, devices for supporting a plurality of pins and feeding them forward by gravity, means to release the pins one by one from the feeding devices, means for holding each pin frictionally when it is released, and means for moving each pin when it is released into operative relation with its coil guard as the latter is presented.

90 10. A machine for assembling safety pins and coil guards therefor comprising a carrier for the guards, means for advancing the carrier with a step-by-step motion, devices for supporting a plurality of pins and feeding them forward by gravity, a device for truing the position of the pin as it is released from the feeding devices, and means for moving each pin as it is released into operative relation with its coil guard as the latter is presented.

95 11. A machine for assembling safety pins and coil guards therefor comprising a carrier for the guards, means for advancing the carrier, feeding devices for the pins, a reciprocating notched plate to true the position of and guide each pin as it is released from the feeding devices, and means for moving each pin into operative relation with its coil guard as the latter is presented.

100 12. A machine for assembling safety pins and coil guards therefor comprising a carrier for the guards, means for advancing the carrier, feeding devices for the pins, means for moving each pin as it is released from the feeding devices into operative relation with its coil guard as the latter is presented, and a yielding point guide to direct the point of the pin as it is so moved.

105 13. A machine for assembling safety pins and coil guards therefor comprising a carrier having a series of dies to receive the guards, means for advancing the carrier step by step to place each guard in position

for receiving its pin, and means for crimping the guard on the coil of the pin while the guard is in the die.

14. A machine for assembling safety pins and coil guards therefor comprising a rotary carrier having a series of dies to receive a series of coil guards, means for advancing the carrier with a step-by-step motion to bring each guard in succession to a point to receive the pin, and means for crimping the guard on the coil of the pin while the guard is in the die.

15. A machine for assembling safety pins and coil guards therefor comprising a carrier having a dished recess to receive the guard and the pin, a reciprocating head, and pair of pinching jaws carried by said head and adapted to coöperate with the dished recess to crimp the guard about the coil of the spring.

16. A machine for assembling safety pins and coil guards therefor comprising a carrier for the guards, means for causing the point member of each pin to pass through its coil guard and place the coil in operative relation with the guard, and means for crimping each guard about the coil of its pin while the guard is in the die.

17. A machine for assembling safety pins and coil guards therefor comprising a carrier for the guards, means for feeding the pins, means for releasing the pins one by one, means for causing the point member of each pin to pass through its coil guard and place the coil in operative relation with the guard, and means for crimping the guard about the coil of the pin.

18. A machine for assembling safety pins and coil guards therefor comprising a carrier for the guards, means for feeding the pins, means for releasing the pins one by one, means for moving each pin as it is released into operative relation with its guard, a reciprocating head, and a pair of pinching jaws carried by the head and adapted to crimp each guard on the coil of its pin.

19. A machine for assembling safety pins and coil guards therefor comprising a carrier for the guards, means for feeding the pins open, means for moving each pin into operative relation with its guard, a supporting rail for one member of the pin, a reciprocating head, and a finger carried by said head to push the other member of the pin into closing relation with the first named member.

20. A machine for assembling safety pins and coil guards therefor comprising a carrier for the guards, means for feeding the pins open, means for moving each pin into operative relation with its guard, a supporting rail for one member of the pin, a reciprocating head, a finger carried by said head to push the other member of the pin into closing relation with the first named

member, and a second finger carried by said head to hold the pin and guard in position in the carrier during the closing operation.

21. A machine for assembling safety pins and coil guards therefor comprising a rotary carrier having a series of dies to receive the coil guards, such carrier and dies being slotted from the edge of the carrier, means for assembling each pin and its guard, means for closing each pin, and means for holding the pin and guard in position in the carrier during the closing operation.

22. A machine for assembling safety pins and coil guards therefor comprising a rotary carrier having a series of dies to receive the coil guards, such carrier and dies being slotted from the edge of the carrier, means for assembling each pin and its guard, means for closing each pin, a reciprocating head and finger carried by said head to hold the pin and guard in position in the carrier during the closing operation.

23. A machine for assembling safety pins and coil guards therefor comprising a carrier having dies to receive the coil guards and the pins, the dies and carrier being slotted from the edge of the carrier, means for assembling each pin with its guard in the carrier, and means for extracting the assembled pin and guard from the carrier.

24. A machine for assembling safety pins and coil guards therefor comprising a carrier having dies to receive the coil guards and the pins, the dies and carrier being slotted from the edge of the carrier, means for assembling each pin with its guard in the carrier, a reciprocating head, gripper jaws carried by said head, means to cause the jaws to grip the pin as the head approaches the carrier, and means to open the jaws to release the pin when the head is withdrawn from the carrier.

25. A machine for assembling safety pins and coil guards therefor comprising a carrier having dies to receive the coil guards and the pins, the dies and carrier being slotted from the edge of the carrier, means for assembling each pin with its guard in the carrier, a reciprocating head, frictionally pivoted gripper jaws coöperating with the carrier to grip the pin as the head approaches the carrier, a lever to open the jaws, and a stop coöperating with said lever as the head withdraws from the carrier to cause the lever to open the jaws and release the pin.

26. A machine for assembling safety pins and coil guards therefor comprising a carrier having a series of dies to receive the guards, means for advancing the carrier step by step, means for causing the point member of each pin to pass through its coil guard and place the coil in operative relation with the guard, means for extracting the pin from the carrier and releasing it,

and means for ejecting the pin from the machine as it is released by the carrier.

27. A machine for assembling safety pins and coil guards therefor comprising a carrier for the guards, means for assembling each pin with its guard in the carrier, a reciprocating head, gripper jaws carried by said head, means for causing the jaws to grip the pin as the head approaches the carrier, means to cause the jaws to release the head when it is withdrawn from the carrier, and means to eject the pin from the machine when it is released from the gripper jaws.
- 15 28. A machine for assembling safety pins and coil guards therefor comprising a carrier for the guards, means for assembling

each pin with its guard in the carrier, a reciprocating head, gripper jaws carried by said head, means for causing the jaws to grip the pin as the head approaches the carrier, means to cause the jaws to release the head when it is withdrawn from the carrier, and a spring-pressed, pivoted ejector plate adjacent to the path of the gripper jaws, yielding to permit the movement of the reciprocating head with the gripper jaws and swinging forward under the influence of its spring to eject the pin as it is released from the gripper jaws.

This specification signed this twelfth day of May, A. D. 1915.

EDWARD CAIRNS.
